U.S. Cl. D95—3

Fig. 1   *Fig. 2*   *Fig. 3*

Fig. 4

Fig. 5

FIG. 1 is a side elevational view of a knife showing my new design;

FIG. 2 is a top plan view;

FIG. 3 is a bottom plan view;

FIG. 4 is a front elevational view; and

FIG. 5 is a rear elevational view.

The design is characterized by an elongated, tapered handle having diagonal ends at opposed acute angles to the handle axis and a blade portion adjacent the handle which forms a V-shaped appearance with the diagonal handle end.

I claim:

The ornamental design for a knife, substantially as shown.
